UNITED STATES PATENT OFFICE.

FIRMIN SILVAIN LEPINTE, OF VINCENNES, FRANCE.

HORSESHOE.

SPECIFICATION forming part of Letters Patent No. 357,014, dated February 1, 1887.

Application filed February 23, 1886. Serial No. 192,886. (No model.) Patented in France April 23, 1885, No. 168,451, and in England February 3, 1886, No. 1,603.

To all whom it may concern:

Be it known that I, FIRMIN SILVAIN LE-
PINTE, a citizen of France, residing at Vin-
cennes, in the Republique of France, have in-
5 vanted a new and useful Improved Roughing
for Horseshoes, (for which I have obtained a
patent in France, dated April 23, 1885, No.
168,451, and made application for a patent in
Great Britain, dated February 3, 1886, No.
10 1,603,) of which the following is a specification.

The essential feature of this invention con-
sists in the use of a roughing-nail having a
rectangular-tapering neck or head with
sharply-formed edges that fit accurately in a
15 corresponding rectangular tapering hole in the
shoe, into which the nail consequently wedges
itself tightly, preventing all chance of shaking
loose, while the thin shank of the nail is curved
and terminates in a chisel shaped end, so that
20 in driving in the nail the chisel-point of the
curved end readily penetrates between, so as
to project beyond the shoe and the hoof, and
in then being bent sharply over the edge of
the shoe it holds the nail firmly in position in
25 its hole, the object of this construction being
that the roughing-nail can be fixed without
the aid of a farrier, and without any other tools
than a hammer, or even a stone, and may be
as readily removed on prizing up the end of
30 the nail by a chisel or strong knife.

The invention will be readily understood on
reference to the accompanying drawings, in
which—

Figure 1 shows a side view of a horseshoe
35 with the roughing applied to it. Fig. 2 is a
bottom view of the same. Figs. 3, 4, and 5
show different forms of the roughing-nails;
and Fig. 6 shows a section through the shoe
with the roughing-nail fixed thereto.

40 The horseshoe is made with the ordinary
holes for nailing on, and in addition it has four
tapering holes formed straight through it for
the reception of the roughing-nails, two, *a a'*,
at the heel ends, and two others, *b b'*, near the
45 toe, the holes being made with a taper exactly
corresponding to the taper of the roughing-
studs, as shown more clearly at Fig. 6. Should
these holes become deformed somewhat on
bending the shoe when fitting it exactly to the
50 horse's hoof, they should afterward be brought

to the proper shape again by driving in the
punch or die used in forming the holes. This
may also be done with regard to the two rear-
most holes for the ordinary nails, which might
in need also serve for receiving the roughing- 55
studs.

The holes for the roughing-studs must be
sufficiently splayed to enable the punch or die
to deliver easily therefrom, and they should be
formed as near as practicable to the outer edge 60
of the shoe. The roughing-studs, which are
conveniently made in two or more different
sizes to suit different-sized shoes, are shown in
side view, front view, and plan in two varieties
at Figs. 3, 4, and 5. They consist of the shank 65
d, the neck *c*, and the head *f*. The neck, which
may either be of square section, as at Fig. 3,
or oblong, as at Figs. 4 and 5, is formed with a
suitable taper from the head to the shank,
which in Fig. 3 is formed with a suitable out- 70
ward curvature, and has a sharp chisel-shaped
end, *d'*.

The head *f* may either be square, as at Fig.
3, or round, as at Fig. 5.

For fixing on the roughing-studs, assuming 75
the shoe to be secured in the ordinary manner
to the hoof, the farrier, holding the stud with
its head inclined slightly outward and the
shank inserted in the hole, drives it in with
gentle blows, whereupon the curved end of the 80
shank will appear between the upper outer
edge of the shoe and the hoof, the curved form
of the shank causing it of itself to pass outward
between the shoe and hoof and to curve over
the edge of the shoe as the stud is driven in. 85

Should the hole in the shoe not be situated
sufficiently near the edge to enable the shank
of the stud to penetrate outward, as described,
a passage may be formed for it in the first in-
stance by driving a punch in between the shoe 90
and the hoof at the corresponding place where
the shank has to penetrate.

For securing the stud when driven in, as de-
scribed, the projecting shank is first seized with
the pinchers and is pulled firmly in an upward 95
direction, and after striking firmly against the
head while still holding the shank with the
pinchers so as to form an angular bend on the
shank where it passes out of the hole in the shoe,
the free end of the shank is then bent sharply 100

downward over the edge of the shoe by striking it with the hammer, when it will be firmly secured in position, as shown at Fig. 6.

For afterward removing the stud again the bent shank is opened out by a chisel or punch, whereupon the stud will be readily extracted by simply striking the head in the downward direction while holding the hoof in a raised position, when it will either fall out of itself or be readily pulled out with the pinchers.

It will be evident that owing to the simple mode of fixing the roughing-studs they may be readily secured by any one without the aid of a farrier or any special tools, an old horse-shoe or a stone being sufficient to drive them in and rivet them down.

The shank of the stud may be left straight by the manufacturer, as shown at Fig. 4, and only be bent to the required extent before insertion in the shoe.

Although I prefer to make the studs with a special head, as shown, yet they may also be employed without this.

Having thus described the nature of my invention and the best means I know for carrying the same into practical effect, I claim--

1. An improved roughing for horseshoes, consisting in rectangular tapering holes formed at suitable points of the shoe, and roughing studs or nails formed with a rectangular-shaped 30 tapering neck or head fitting the said holes closely with a wedging action and having a thin curved shank with chisel-shaped end, which projects out between the shoe and the hoof, and is bent sharply down over the edge 35 of the shoe for fixing the nail, substantially as herein described.

2. A roughing stud or nail having a rectangular-shaped neck or head of uniform taper adapted to fit a correspondingly-tapered hole 40 in the shoe, and a thin curved shank with chisel-shaped end adapted to penetrate between the shoe and the hoof, substantially as herein described.

In testimony whereof I have signed my name 45 to this specification, in the presence of two subscribing witnesses, this 9th day of February, A. D. 1886.

FIRMIN SILVAIN LEPINTE.
